UNITED STATES PATENT OFFICE.

JOHN M. GLASER, OF BUFFALO, NEW YORK, ASSIGNOR TO U. S. HAME COMPANY, OF BUFFALO, NEW YORK.

HAME AND PROCESS OF MAKING THE SAME.

Application filed July 30, 1926. Serial No. 126,051.

This invention relates to hames of the kind made of metal tubing, and to processes of making the same.

Hames have heretofore been made of tubing which was shaped while hot into the desired form, and hames have also been made by folding or wrapping sheet metal around a wooden filler or insert. Owing to the fact, however, that tubular hames have heretofore always been shaped while hot, it was impossible to use wooden inserts in connection with these tubular hames. There are, however, some very decided advantages in the use of a wooden insert in a metal hame, both from the standpoint of strengthening or reinforcing the hame and facilitating the attachment of the usual wear leathers to the hames, and from the standpoint of facilitating the manufacture of hames of this kind.

The objects of this invention are to provide a hame made of metal tubing and provided with a reinforcing member or insert of wood or other nonmetallic material, the shape of which is changed during the course of manufacture of the hames, in accordance with changes in the shape of the tube, so that the insert is compressed in the tube and therefore remains in fixed relation thereto and in intimate contact with the sides of the hame to prevent denting thereof; also to provide a hame of this kind in which the holes in the metal tube may be punched instead of drilled; also to provide an improved process of manufacturing hames of this kind which results in an economic production of the tubular hames with nonmetallic inserts; also to provide a process whereby a tubular shell of a hame, while in substantially circular cross sectional form receives a nonmetallic insert of substantially the same cross sectional form, and in which process the cross sectional shape of the hame shell or tube and the insert are simultaneously changed by a pressing operation; also to provide an improved process for making hames in accordance with which the ends of the hames are tapered or of reduced cross sectional area and at the same time the thickness of the metal in the tapered end portions is increased so that the strength of these end portions is considerably greater than in hames heretofore made; also to provide a process of making hames in accordance with

which the wooden or nonmetallic inserts used inside of the hame tubes need not be shaped or formed to conform with the ultimate shape of the hame tubes, but are so shaped or formed by the same operations by means of which the tube or shell of the hame is changed in form; also to improve processes of manufacturing hames by punching holes into the tubular shell of the hame after the hame has been shaped into its desired form; also to improve processes of manufacturing hames in other respects hereinafter specified.

In the accompanying drawings,

Fig. 1 is a longitudinal view of a tube from which the shell of the hame is made.

Fig. 2 is an end view thereof.

Fig. 3 is a longitudinal view of the tube after the first swaging operation has been performed thereon.

Fig. 4 is a longitudinal view of the filler or insert member for use within the hame.

Fig. 5 is an end view thereof.

Fig. 6 is a central, sectional view of the hame tube shown in Fig. 3, with the insert member positioned therein.

Fig. 7 is a longitudinal view partly in section, showing the other end of the tube tapered or swaged to inclose the insert member within the tube.

Fig. 8 is an end view thereof.

Fig. 9 is a side view thereof showing the tube after one side thereof has been flattened.

Fig. 10 is a section thereof on line 10—10, Fig. 9.

Fig. 11 is a front view of the hame showing the same after the ends of the tube have been curved or bent.

Fig. 12 is a side view of the hame showing the holes punched therein.

Fig. 13 is a view of the opposite side of the hame.

Fig. 14 is a front elevation, partly in section, of a completed hame with the various parts or attachments secured thereto.

In manufacturing hames in accordance with my improved process a tube is used which is made of a proper grade of steel or other metal to withstand the several operations to which the tube is subjected during the course of formation of the shell of the hame, without rupturing the metal or crystallization of the same. The tube may be of

the seamless kind or it may be a seamed or welded tube. The tubing from which these hame shells are made is then cut into the desired lengths as shown in Fig. 1, the lengths 5 being somewhat shorter than the lengths of the ultimate hame shell.

The next step in my process consists in tapering one end of the tube, from near the middle portion to one end thereof; this 10 tapering operation may be done in any suitable or desired manner, and may, if desired, be done while the metal is at a forging heat. Preferably, however, this operation is done cold and by means of a swaging machine or 15 apparatus which swages the metal into the desired shape. The swaging operation causes the tubes to become somewhat elongated and also considerably increases the thickness of the metal near the end portions 20 of the tube, the increase in thickness being more or less proportional to the decrease in the outside diameter of the tube. The swaging operation of this end of the tube may, if desired, be done in two steps, for example, 25 the tube may be first swaged approximately to its desired size, and the tube may then be heat treated or annealed, so that the grain of the metal may adjust itself to the change in shape by the annealing operation, and the 30 tube may then be finally swaged into its final form after the metal has again cooled off. By tapering the end of the tube in two steps, crystallization of the metal is prevented and 35 none of the strength of the metal is lost due to the swaging operation. With certain grades of metal, the annealing is not necessary and may be entirely omitted.

The tube A with one end tapered, as shown 40 in Fig. 3 is then ready to receive an insert member B which may be made of wood or other nonmetallic substance. In the particular construction shown the insert member B is made in two pieces or sections, but it will 45 be understood that this member may be made in one piece or in a larger number of pieces. The insert B is tapered approximately in accordance with the ultimate taper desired at the two ends of the tube and the insert member 50 is preferably approximately round or circular in cross section so as to conform substantially with the interior of the tube A. The insert member is shown in Fig. 6 as positioned within the tube, and the tube with 55 the insert member in position therein is then ready for the next operation, which consists in tapering the lower end of the tube A. This operation must, of course, be done while 60 the tube is cold, since the wood or insert member B would be burned or damaged if the tube A were heated. Consequently the tapering of the lower end of the tube is preferably done by means of a swaging process, which again causes a slight elongation of the tube and a considerable increase in thickness of 65 the metal at the reduced end of the tube. By

means of the second swaging operation the wooden or nonmetallic insert member is securely confined within the tube. The tube A is shown in Fig. 7 with its lower end tapered and the insert member confined therein. The insert member fits rather loosely into the tube and it has been found unnecessary to have the insert member fit very snugly into the tube during this step of the process. Furthermore these tubes sometimes contain 70 a burr on the inside thereof due to the formation of the seam, and this burr serves to space the insert member at a slight distance from the inner periphery of the tube. Whether or not the insert member conforms closely 75 with the interior of the tube, however, depends considerably upon the material of which the insert member is made. When hard wood is used it has been found unnecessary to have the insert member driven into or 80 tightly fitted into the tube while the tube is in the shape shown in Fig. 7.

The tube may then be trimmed to the correct length by cutting or shearing off portions of one or the other end thereof. This 85 operation is greatly facilitated by first swaging the ends of the tube, since by the swaging operation the thickness of the metal at the ends of the tubes is so increased that the ends 90 may be sheared off without collapsing the 95 ends of the tubes.

The next operation to which the tube is subjected is that of changing the cross sectional shape thereof while the insert member is in place in the tube. This operation is performed on the hame for the purpose of adapting the hame to cooperate better with the collar or other parts of the harness and consists in flattening to a certain extent one face or side of the hame and bending the other face 100 approximately into the cross sectional shape shown in Fig. 10. This may be done by means of dies in a press, and the result of applying pressure to the exterior of the tube by the dies is that the tube is pressed into the 105 shape shown in Fig. 10 and the insert or filler is also compressed to follow somewhat the general contour of the interior cross section of the tubes. The side edges of the filler, however, need not entirely fill the side portions 110 of the tube or shell, a small amount of space at the edges of the tube or shell being left unfilled by the filler or insert, which space results from the use of a filler member which does not entirely fill the interior of 115 the tube A while the same is of circular cross section, as shown in Figs. 6 and 7. By using a filler which does not entirely fill the interior of the hame tube, as shown in Fig. 10, the filler, if made of wood, is not splintered or 120 broken up, and the filler is also compressed and compacted so as to offer greater resistance to denting of the hame than would be the case if the wood or nonmetallic filler were not compressed. Consequently the filler al- 125 130

though pressed out of its original shape, has been found to possess practically its full strength and is merely compressed out of its original shape and is not splintered or broken.

The bending of a tube of this kind with a filler or insert therein, also has a very important advantage over the bending of a tube without such an insert, namely that it is impossible by means of ordinary dies to change the shape of a tube of circular cross section in one operation in such a manner that one wall thereof will be flat, since the tendency is that the portion of the tube along the flat side of the die will buckle inwardly and thus instead of forming a substantially flat or straight face on one side of the hame, will form a slightly concaved face, which is objectionable. The use of an insert member, however, prevents this concaving of the flat side of the tube and makes it possible in a single pressing operation to form the tube with a truly flat side, it being obvious that the insert member offers considerable resistance to compressing of the same out of its normal shape, and this resistance also prevents the inward buckling or concaving of the flat side of the hame tube. Without an insert member the true flattening of one side of the hame would require a number of die operations, which would materially increase the cost of hames, and which might damage the grain structure of the metal of the tube.

The hame with one side thereof flattened is then subjected to the action of bending dies which bend the ends of the hame in opposite directions approximately into the shape shown in Fig. 11, so that the hame will readily fit on the collar of an animal's harness. It will be noted that the upper bent end *c* of the hame is of comparatively small diameter, having been greatly reduced in size by the swaging operation. Consequently the metal in the upper bent end *c* of the hame is of considerably increased thickness so that this part of the hame can be readily bent without buckling the metal of the tube *A* of the hame. The lower portion of the hame, however, must be bent at a part thereof having substantially the maximum cross sectional area, this portion of the hame having been subjected to the least amount of swaging action. In order to make it possible to have this part of the hame bent by means of the usual bending dies, it is necessary for the insert member *B* to extend into the same and to be bent with the lower end *c'* of the hame. Consequently during the bending of this portion of the hame the insert member *B* is also bent and also prevents buckling or distortion of the tube of the hame during the bending action. The bending operation may be effected by any suitable bending dies, and the front and rear faces of the tapered hame tube are preferably held or confined by means

of suitable holding dies during the bending operation.

After the ends of the hame have been bent, the hame is ready for the forming of the holes therein by means of which the various attachments or parts may be secured to the hame. Heretofore the forming of holes in tubular hames had to be done by means of drilling, and the punching of holes was rendered impossible due to the fact that the portions of the tube adjacent to the punches would collapse or be dented inwardly sufficiently to damage the tube. In accordance with my improved process, however, it is possible to punch holes in the tube of the hame for the reason that the filler member *B* prevents collapsing or inward denting of the portions of the hame adjacent to the punches. Since a drilling operation is many times more expensive than a punching operation, it is obvious that considerable economy is effected in so forming a hame that the holes therein can be punched rather than drilled. Furthermore the punching of the holes has an advantage in that the metal of the hame tube is pressed inwardly to a slight extent around the punched hole, and this in the case of the holes *d* shown in Fig. 14 forms a countersunk portion or depression around the holes, into which the riveted ends of the bolts or rivets securing the attachments or parts on the hame may enter and thus form a smoother exterior on the hame, which reduces the wear on adjacent harness parts. The several holes *d'* through which nails attaching the wear leather *E* to the hame may pass, can be formed in one operation by means of a set of dies. It is obvious that the reinforcing member also greatly strengthens the hame, since the bolts or rivets *f* of the usual trace or draft connection *F* extend both through the tube and through the filler member, and since the riveted heads or ends of the bolts or rivets *f* are countersunk in recesses in the opposite side of the hame, it will be obvious that these recesses bear against the insert member, which assists the hame shell in resisting the strains transmitted by draft connection to the hame. The lower bolt or rivet *g* which connects the bracket or support *G* for the hame strap loop *g'* also preferably passes through the wooden insert member *B*, but the rivet connecting the upper portion of this bracket *G* is arranged above the upper end of the wooden insert *B*, so that the holes *d* therefor is formed by punching through the metal of the tube itself. Here again, however, the swaging operation makes this punching possible for the reason that the metal in this portion of the hame tube has been increased in thickness to such an extent that this hole can be easily punched through the tube without collapsing or denting the metal of the tube except for forming a slight depression around the hole, which receives

the portion of the rivet head. Similarly the hole d^3 through the lower portion of the hame can be punched through this side of the hame because of the thickness of the metal at this end of the hame due to the swaging operation. The hole d^3 serves to permit the usual end loop H of the hame to be secured thereto.

The hame formed in accordance with this process is provided with a wooden insert member B arranged within the tube A , which wooden insert member is originally of substantially circular cross section and is compressed into a shape corresponding with the interior of the hame tube, by changes in the shape of the hame tube. The hame tube is provided at opposite ends with swaged portions which reduce the diameter of the tube but increase the thickness of the metal thereof at the swaged portion, approximately in proportion to the reduction of the outside diameter of the tube. This increase in thickness consequently reinforces the end portions of the hame, while the intermediate portions thereof are reinforced by the insert member B of wood or other suitable material. The hame furthermore is provided with punched holes d' through which tacks or nails for securing the wear leather E to the hame may pass, and with punched holes for the bolts or rivets of the various hame attachments or parts, which punched holes are countersunk due to the punching operation to partly receive the swaged over portions of the ends of the rivets securing the attachments or parts to the hame. The use of an insert member of this kind not only facilitates the manufacture of the hame and makes possible certain economies such as the punching of holes instead of the drilling of the same, but also greatly reinforces the portion of the hame subjected to the greatest strain, and resists denting of the hame. The fact that the wood or nonmetallic insert in the shell of the hame is compressed or compacted due to the change of shape of the tube while the insert member is in place therein enables the hame to offer greater resistance to denting than in hames in which the wood is covered by sheet metal, since in the latter hames the wood is not compressed. Furthermore the compressed wood offers a more secure hold for the nails or tacks passing through the holes d' to secure the wear leather E in place. The hame described also has the advantage that the end portions thereof which are not reinforced by the insert member B are of considerably increased thickness due to the swaging operation, and therefore offer increased resistance to strains.

60 I claim as my invention:—

1. A hame including an outer tubular shell having its ends tapered and having its intermediate portion pressed into non-circular cross sectional shape, and a wooden insert in said shell which is compressed by the press-

ing of said tube into a non-circular cross sectional shape and retained in non-circular shape by said tube.

2. A hame including an outer shell made of a metal tube having its ends tapered, said shell being pressed into a non-circular cross sectional shape, and a non-metallic insert compressed by said shell into a non-circular cross sectional shape.

3. A hame including an outer shell made of a metal tube having its ends tapered and curved out of alignment with the intermediate portion of said shell, and a non-metallic insert in the intermediate portion of said shell and extending into a curved portion of said shell, said insert being shaped by the curving of said shell to conform with the interior of said shell.

4. A hame including an outer shell made of a metal tube having its ends tapered and curved out of alignment with the intermediate portion of said shell, said shell being pressed into a non-circular cross sectional shape, and a normally straight wooden insert of substantially circular cross section which is compressed by said shell into non-circular cross sectional shape and the ends of which extend into a curved portion of said shell and being shaped by the curving of said shell to conform with the curvature of adjacent portion of said shell.

5. A hame including an outer shell made of a metal tube and having a non-metallic insert within said shell, the ends of said shell being of reduced diameter and bent in opposite directions, said shell having holes punched therein at portions thereof confining said insert.

6. A hame including a shell made of a metal tube having swaged ends of reduced outside diameter and having the metal in the reduced ends of greater thickness than at the portions thereof of greater diameter.

7. A hame having a tubular metal shell provided with a non-metallic reinforcing insert intermediate of the ends thereof, the end portions of the tubular shell being tapered and the metal in said tapered portions being of greater thickness than the metal in the portions of said hames which are reinforced by said insert.

8. A hame including an outer metal shell and a non-metallic insert in the intermediate portion thereof, the ends of the hame being of reduced outside diameter and having thicker walls than the intermediate portion of the hame, whereby the ends of the hame are reinforced by the increased thickness of the walls of the metal shell and the intermediate portion of the hame is reinforced by said insert.

9. A process of making hames which includes tapering one end of a substantially cylindrical tube, placing into the tube an insert of non-metallic material, bending said

tube to change the cross sectional shape thereof and of said insert, and bending an end of the tube to place the axis of the bent end out of alinement with the axis of the intermediate portion of the tube.

10. A process of making hames which includes placing a non-metallic insert loosely into a tube of substantially circular cross section, pressing the tube and insert into a shape 10 of non-circular cross section, said insert serving to prevent excessive inward deflection of portions of said tube, and bending an end of the tube to place the axis of the bent end out of alinement with the axis of the intermediate portion of the tube.

11. A process of making hames which includes placing a non-metallic insert loosely into a tube of substantially circular cross section, pressing the tube and insert to flatten one side of said tube and insert, said insert resisting the formation of a concave surface at said flat side of said tube, and bending an end of the tube to place the axis of the bent end out of alinement with the axis 25 of the intermediate portion of the tube.

12. A process of making hames having tubular shells, which includes reducing an end of a substantially cylindrical tube by swaging said end while cold to form a taper 30 on said end, heat-treating said tube, placing a non-metallic insert of corresponding taper into said tube and then tapering the other end of said tube by swaging while cold, to confine the non-metallic insert within the 35 tube.

13. The process of making hames having tubular shells and non-metallic inserts, consisting of partly forming a taper on one end of a substantially cylindrical tube by a swaging 40 operation, annealing said tube, completing the forming of the taper on said end of the tube, placing a non-metallic insert of corresponding taper into said tube and then tapering the other end of said tube by swaging 45 while cold, to confine the non-metallic insert within the tube.

14. A process of making hames having tubular shells and non-metallic inserts, which includes tapering one end of a substantially 50 cylindrical tube, placing an insert of non-metallic material into said tube from the larger end thereof, tapering said larger end of said tube while cold by a swaging operation, and flattening a side of said tube and 55 producing a corresponding change in the shape of the non-metallic insert.

15. A process of making a hame having a tubular shell and a non-metallic insert within the shell, which includes tapering one end of 60 a substantially cylindrical tube, placing into said tube an insert of non-metallic material and corresponding approximately to the interior cross section of said tube, tapering the other end of said tube to confine said insert 65 therein, pressing said tube and the insert con-

tained therein into non-circular cross sectional shape, and bending a portion of said tube and of said insert in a direction transverse to its length.

16. A process of making hames having a 70 tubular shell and a non-metallic insert, which includes tapering one end of a substantially cylindrical tube, placing into said tube an insert of non-metallic material having its opposite ends tapered, one end of said insert fitting approximately into the tapered end of the tube, tapering the other end of said tube, and bending an end of said tube and said insert contained therein in a direction transverse to the length of said tube.

17. A process of making hames having tubular metal shells and non-metallic inserts arranged in the intermediate portions of said shells, consisting of swaging the ends of said shells to form tapered ends on said tube and at the same time increase the thickness of the metal in the tapered end, and punching holes through portions of the hames having metal of increased thickness.

18. The herein-described process of making 90 hames, consisting of forming a straight tube of substantially uniform diameter into a tube, having one end tapered, placing an insert into said tube, and then forming a taper on the other end of said tube to confine said 95 insert in said tube.

19. The herein-described process of making hames, consisting of forming a straight tube of substantially uniform diameter into a tube, having one end tapered, placing an insert 100 into said tube, and then forming a taper on the other end of said tube and bending the ends of said tube to confine said insert in said tube.

20. The herein-described process of making 105 hames, consisting of forming a straight tube of substantially uniform diameter into a tube, having one end tapered, placing an insert into said tube into engagement with said tapered end, and then tapering and curving 110 the other end of said tube while said insert is in place therein.

21. The herein-described process of making hames, including an outer part made of a steel tube, and a reinforcing filler of wood, 115 consisting of tapering an end of said steel tube while the wood is in place therein to reduce the diameter of an end of said tube, and bending said tube with the wood in place therein so that the wood is formed in accordance with the shape of said tube, the forming of the tube serving to secure the wood in place in said tube.

22. The process of making hames having tubular shells, which consists of swaging one 125 end of a tube of substantially uniform circular cross section to form tapering ends of smaller diameter and increased thickness of metal, placing a non-metallic insert into the intermediate portion thereof, and swaging 130

the other end of the tube in a similar manner, said non-metallic inserts reinforcing the portions of the hames in which the thickness of the metal is not increased.

5. 23. A hame including a shell made of a metal tube having swaged ends of reduced diameter and having the metal in the reduced

ends of greater thickness than at the portions thereof of greater diameter and having the swaged ends bent to place the axes of the bent ends out of alinement with axis of the intermediate portion of the hame.

JOHN M. GLASER.
